UNITED STATES PATENT OFFICE.

MINER L. KILLITS, OF ST. LOUIS, MISSOURI.

DESIGN FOR A COIN-CONTROLLED-VENDING-MACHINE CASING.

SPECIFICATION forming part of Design No. 37,328, dated February 7, 1905.

Application filed June 6, 1904. Serial No. 211,410. Term of patent 3½ years.

To all whom it may concern:

Be it known that I, MINER L. KILLITS, a citizen of the United States, residing in the city of St. Louis and State of Missouri, have invented a new and original ornamental Design for a Coin-Controlled-Vending-Machine Casing, which is shown in the accompanying drawings, in which—

Figure 1 is an elevation of a coin-controlled-vending-machine casing embodying my design, and Fig. 2 is a plan view of the same.

What I claim as new, and desire to secure by Letters Patent, is—

The ornamental design for a coin-controlled-vending - machine casing, substantially as shown.

MINER L. KILLITS.
